CLAIM

The ornamental design for a ventilation separator as shown and described.

DESCRIPTION

FIG. 1 is a front perspective view of a ventilation separator showing the new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof; and,

FIG. 7 is a rear elevational thereof.

The ventilation separator includes a symbolic break along its width. The break lines, brackets, and the area between the break lines form no part of the claimed design.
